(57) CLAIM

The ornamental design for a lighter, as shown and described.

DESCRIPTION

FIG. 1 is a perspective view of the lighter my new design, illustrating the lighter being actuated at an ignition position. FIG. 2 is a front view of the lighter at the ignition position. FIG. 3 is a rear view of the lighter at the ignition position. FIG. 4 is a left view of the lighter at the ignition position. FIG. 5 is a right view of the lighter at the ignition position. FIG. 6 is a top view of the lighter at the ignition position. FIG. 7 is a bottom view of the lighter at the ignition position; and,

FIG. 8 is a perspective view of the lighter, illustrating the lighter at a non-ignition position.

The broken lines represent unclaimed portions of the article. All of the broken lines form no part of the claimed design.
